UNITED STATES PATENT OFFICE.

WILLIAM C. FREE, OF ROCKFORD, ILLINOIS.

SEWING-MACHINE.

1,342,435.

Specification of Letters Patent.

Patented June 8, 1920.

Application filed January 31, 1916. Serial No. 75,194.

To all whom it may concern:

Be it known that I, WILLIAM C. FREE, a citizen of the United States, residing at Rockford, in the county of Winnebago and 5 State of Illinois, have invented certain new and useful Improvements in Sewing-Machines, of which the following is a specification.

The sewing machine cabinets hitherto in 10 use have ordinarily consisted of boxes or closets comprising stationary back and side walls inclosing the machine and a front door extending the width of the cabinet and designed for access to the machine. There 15 are a number of objections to a cabinet of this character, among which may be mentioned that it so closely surrounds the machine and the legs and feet of the operator as to be uncomfortably warm in a room at 20 ordinary temperatures, and particularly during hot weather. Furthermore if the sewing machine head is set symmetrically in the center of the cabinet, which is the preferred position, the needle being close to one side 25 of the cabinet requires the operator, in order to be directly opposite the needle as he should be, to sit closely cramped against the adjacent wall of the cabinet, or else to straddle the wall. So serious is this disadvan- 30 tage that in some makes of machines the machine head is set asymmetrically with respect to the cabinet or the cabinet extended upon the needle side thereof in order to overcome the difficulty, thus making the cabinet 35 objectionably large and unwieldy. In my improved sewing machine this objection is obviated by not only hinging the front wall or door of the cabinet but also hinging that side wall which is adjacent the needle, the 40 door and side being hinged respectively to the edges of the stationary side and back walls and meeting when closed to form a corner of the cabinet. The walls are mounted upon the frame proper of the machine which 45 is so formed and designed with reference to the cabinet that it supports the walls of the latter at the corners and particularly the free edges of the hinged front and side walls when closed, and that end of the frame ad- 50 jacent the hinged door is so formed that it presents no material obstacle to the operator sitting with the center of his body opposite the needle or transferring his foot from the outside of the frame upon that 55 side to the treadle, or reversely. When

closed the cabinet of my machine effectually conceals the machine proper and appears like any other closed cabinet, but is readily and quickly thrown open into position to use the machine.

In the following specification and in the drawings accompanying and forming part of this specification, I have described a preferred form of the invention. It is to be understood, however, that the specific disclosure is for the purpose of exemplification only and that the scope of the invention is defined in the following claims.

Referring to the drawings Figure 1 is a perspective view of a sewing machine embodying my invention and Fig. 2 a horizontal section on the broken line 2—2 of Fig. 1.

The sewing machine proper may be of any suitable type, as for example with a drop head as shown, or a stationary head or with 75 a stationary treadle as shown or one which may be raised with the dropping of the sewing machine head. The frame of the machine comprises end frames 3, 4, which are flat on their exterior sides and comprise vertically extending front legs 5, 6, the lower ends of which are formed with outwardly and forwardly projecting shoulders 7, 8, above the crotch within which the rollers 9, 10, are journaled. The vertical legs extend 80 but a short distance above the rollers and from their upper ends the side frames retreat as at 11, 12, to a plane about midway of the machine where they are formed with vertical risers 13, 14, connected with the 90 upper portions of said frames. The rest of the frame of the machine may be of any desired form and need not therefore be described. The back wall 15, of the cabinet is screwed or otherwise secured to the end 95 frames of the machine and the stationary end wall 16 similarly fastened to that one of the end frames of the machine which is adjacent the same. This end wall extends from the back wall forwardly to the front 100 edge of the corresponding front leg of the machine frame to which it may be secured if desired. The front wall 17 of the machine is hinged to the front edge of the stationary side wall and is of a width to extend beyond 105 the other front leg 5 of the sewing machine frame and to rest against the same when in closed position. The other side or end wall 18 of the machine is pivoted to the edge of the rear wall remote from the fixed side 110

wall and is of a width to extend when closed to the plane of the front edge of the machine frame leg 5, and when closed said side wall rests against and is supported by the flat end frame of the sewing machine. The free edges of the pivoted side wall and front are provided respectively with a catch 19 and keeper 20, which are engaged when the cabinet is closed and may be of any suitable form. The free edges of the side wall and door are correspondingly formed to make a close joint and in the particular construction shown are shouldered to make a matched joint. The walls of the cabinet are formed with downwardly extending leg portions 21 which rest against and conceal the legs of the sewing machine frame when the cabinet is closed and are cut out as at 22 to fit closely over the shoulders of the roller bearings. Where a drop head is employed in the machine a folding leaf 23 which may be of any usual or approved form is hinged to the end of the cabinet having the pivoted wall and when extended is adapted to rest upon the pivoted wall which forms a substantial support therefor.

It will thus be seen that in my improved machine the cabinet when opened gives free and unconfined access to the interior of the machine and permits the operator to sit in the preferred position referred to above with one leg outside the frame, the latter being so formed as not to materially interfere with the comfortable position of the operator's legs and to permit the foot of the operator to be comfortably transferred to outside the machine frame or to the treadle. The cabinet walls when closed are so supported by the frame as to constitute a perfectly rigid structure which perfectly conceals the frame.

I claim:

1. In a sewing machine, a rectangular head supporting frame having legs at its several corners, and a cabinet inclosing and sustained by said frame having a fixed rear wall and a fixed end wall, a front wall pivoted to the front edge of said fixed end wall and a swinging end wall pivoted to the edge of the rear wall. 50

2. In a sewing machine, a frame rectangular in plan, and a cabinet inclosing the same comprising a fixed rear wall secured to said frame, a fixed end wall secured to said frame and extending forwardly to the front plane 55 of said frame, a front wall pivoted to the front edge of said fixed wall and adapted when closed to rest against the front corners of said frame, and a swinging end wall hinged to the edge of the rear wall opposite 60 the fixed end wall and adapted when closed to rest against the adjacent end of the frame and extend to the front plane thereof and engage the free edge of the front wall. 65

3. In a sewing machine, a frame comprising end frames having vertical legs at the front and rear thereof, a rear wall secured to said frame, an end wall secured to one of the end frames, a front wall hinged to the front edge of the fixed end wall and adapted 70 when closed to rest against the vertical front legs of the frame, and a swinging end wall hinged to the edge of the rear wall remote from the fixed end wall and adapted when closed to rest against the corresponding end 75 frame and the front leg thereof and to abut against the free edge of the front wall.

WILLIAM C. FREE.
